UNITED STATES PATENT OFFICE.

CARL HERRMANN, OF NEW YORK, N. Y.

CRACKER-CUTTING DIE.

SPECIFICATION forming part of Letters Patent No. 407,929, dated July 30, 1889.

Application filed April 24, 1889. Serial No. 308,424. (No model.)

To all whom it may concern:

Be it known that I, CARL HERRMANN, of the city, county, and State of New York, have invented a new and Improved Cracker-Cutting Die, of which the following is a full, clear, and exact description.

My invention relates to dies used in cracker-cutting machines, and has for its object to provide a die of this character which may be quickly repaired or partially refaced should it be broken by contact with hard substances in the dough or otherwise.

The invention consists in a cracker-cutting die provided with a face built up of removable sections which may easily be renewed when broken and by any ordinary workman, all as hereinafter described and claimed.

Reference is to be had to the accompanying drawings, forming a part of this specification, in which similar letters of reference indicate corresponding parts in all the figures.

Figure 1 is a bottom plan view of a portion of a cracker-cutting die made in accordance with my invention. Fig. 2 is a transverse section of the die taken on the line $x-x$ in Fig. 1, the die being shown in normal position of use; and Fig. 3 is a bottom perspective view of one section of the die-face.

In its general form the cracker-cutting die shown but in part in Fig. 1 of the drawings is quite similar to other dies of this character—that is to say, it has a box-like main portion A, at the bottom face of which the cracker-cutter or die proper is placed—and it is also provided at its upper part and at one side with a horizontal flange B, provided with a series of pins C, which as the die is reciprocated vertically make air-holes in the sheet of pastry traveling along on an endless bed and prior to the cutting out of the crackers by the die, the holes made by the pins C coming at the centers of the cut crackers. The pins or plungers and the stripper-plate, which push the cut crackers from the die and clear it of scrap dough, are not shown in the drawings, as these form no part of my invention.

It is well known that dies of this character have considerable area at their cutting-face, which is subdivided into many cracker shapes to cut from ten to thirty or more fancy crackers each time the die-face descends through

the sheet of dough. This dough, though usually sifted, often contains hard substances, which, when struck by the sharp internally-serrated edges of one or more of the individual cracker-dies, breaks them and renders the entire die practically useless unless its whole face be ground down level with the deepest broken-away portion of its face and the individual dies be afterward dressed up again or reshaped and refinished. These operations require much time and skilled labor, and are therefore quite expensive, and it is to obviate these disadvantages that my sectional cracker-die is specially designed.

It will be understood that my improvement is applicable to dies designed to produce a number of crackers of any ordinary form, such as round, oval, square, or any fanciful shape having serrated or scalloped edges. As a fair example of the invention, I show the individual cracker-dies on the main die made in round form with interior radial projections to produce round scallop-edged crackers.

I make the whole face of the die except its two end portions in transverse sections D, each of which is formed so as to bisect the center of two adjacent individual cracker-dies $d-d$ at the center of the main die and two half-round individual die portions $d'-d'$ at opposite edges of the die, and which complete the cutting of one row of the crackers as the main die is reciprocated.

Fig. 3 of the drawings clearly illustrates the form of one of the face-sections of my improved die, and shows how much easier it is to form and trim and finish the interior radial cutting ridges or projections E at the faces of the individual dies $d-d$ at the center of the main die when the joints of the sections bisect their center openings, as there are no opposing walls to be encountered by a file or other dressing-tool, as there would be were the die-face cut transversely to leave whole individual dies $d-d$ at the center of the die-section D. It will be noticed that the scrap-openings d^2 of each die-section D lie at its center and between the open-sided half-sections of the individual cracker-dies. The end die-sections D' will of course have only one-half of the end individual die portions $d-d$ formed at their inner edges, as shown at

the left-hand end of Fig. 1 of the drawings, the other end of the main die being broken away.

I purpose making the die-face sections about 5 from one-half to three-quarters of an inch or one inch deep and to connect each section to the face of the die-box A by a couple of screws F F, passed through the side walls of the box and entering threaded holes in the 10 backs of the die-sections, as clearly shown in Fig. 2 of the drawings.

I am not limited to using screws for fastening the removable die-sections to the box or body of the die, as any other equivalent or 15 suitable means for attaching the sections may be adopted within the scope of my invention; but I specially claim the screw-fastenings, as hereinafter set forth.

It is obvious that when a cracker-cutting 20 die made with individual die-sections D D' strikes a hard substance in the dough, and one or two of the individual dies are broken thereby, it is a comparatively simple matter to take out the damaged die-sections by 25 removing their screws F and set in other good die-sections, which, before they are screwed in place, may be dressed down at the back to bring their cutting-edges truly level with the old undamaged sections which may have been 30 worn more or less by use. This substitution of one or more die-sections D, which may be quickly and easily effected, makes practically a new main die, thus saving much expense which otherwise would be entailed in grinding 35 down the entire face of the die and reshaping or forming the ribs E at the interior of the individual dies or cutters, as will readily be understood.

Having thus described my invention, what

I claim as new, and desire to secure by Letters Patent, is—

1. A cracker-cutting die provided with a face consisting of removable or renewable sections having their joints on lines bisecting the openings of the individual cracker-dies, 45 and means for fastening the removable sections to the die box or body, substantially as herein set forth.

2. A cracker-cutting die provided with a face consisting of removable or renewable 50 sections each made with scrap-openings at its center, and provided at opposite edges with halves or sections of the individual cracker-dies, and means for fastening the removable sections to the die box or body, substantially as herein set forth.

3. A cracker-cutting die provided with a face consisting of removable or renewable sections having their joints on lines bisecting the openings of the individual cracker- 60 dies, and provided at the walls of the individual dies with radial or projecting cutters giving scalloped or ornamental marginal form to the crackers, and means for fastening the removable sections to the die box or body, 65 substantially as herein set forth.

4. A cracker-cutting die provided with a face consisting of removable or renewable sections having their joints on lines bisecting the openings of the individual cracker- 70 dies, and fastening-screws passed through the walls of the die into the sections, substantially as herein set forth.

CARL HERRMANN.
